UNITED STATES PATENT OFFICE

137,840

DESIGN FOR A SHEET OF A DECORATIVE WALL MATERIAL OR THE LIKE

William Burton, Chicago, Ill.

Application January 5, 1944, Serial No. 112,169

Term of patent 7 years

(Cl. D59—10)

To all whom it may concern:

Be it known that I, William Burton, a citizen of the United States, residing at Chicago, in the county of Cook and State of Illinois, have invented a new, original, and ornamental Design for a Sheet of a Decorative Wall Material or the like, of which the following is a specification, reference being had to the accompanying drawings, forming a part thereof.

In the drawings—

tive wall material or the like, showing my new design.

Figures 2 through 8, inclusive, are enlarged views of each of the elements of the decorative material shown in Figure 1.

I claim:

The ornamental design for a sheet of a decorative wall material or the like, substantially as shown.

WILLIAM BURTON.
